UNITED STATES PATENT OFFICE.

GEORGE F. SISBOWER, OF BAYSIDE, AND LOUIS E. PITTONI, OF NEW YORK, N. Y., AS
SIGNORS TO MANHATTAN-ROME COMPANY, BRANCH OF ROME METALLIC BED-
STEAD CO., OF LONG ISLAND CITY, NEW YORK, A CORPORATION OF NEW YORK.

COUCH HAMMOCK.

Application filed March 21, 1919. Serial No. 284,131.

To all whom it may concern:

Be it known that we, GEORGE F. SISBOWER, a citizen of the United States, residing at Bayside, New York city, in the county of 5 Queens and State of New York, and LOUIS E. PITTONI, a subject of the King of Italy, residing at New York city, in the county of Queens and State of New York, have invented certain new and useful Improvements 10 in Couch Hammocks, the following being a full, clear, and exact disclosure of the one form of our invention which we at present deem preferable.

For a detailed description of the present 15 form of our invention, reference may be had to the following specification and to the accompanying drawings forming a part thereof, in which—

Fig. 1 is a front view of a hammock provided with our device,

Fig. 2 is a side view thereof with the end sheet removed and

Fig. 3 shows a detail.

Our invention relates to couch hammocks 25 of the well known type wherein the seat frame with mattress thereon is suspended by means of end sheets attached to the end bar of the frame at their lower edges and attached to ropes or chains at their upper 30 edges. Such a hammock is ordinarily provided with a back or windshield detachably secured at each end to the end sheets by means of a connector on each end of the rail which extends along its top edge. The 35 lower edge of the windshield is ordinarily left free or tied by tapes to the back rail of the frame.

In our present construction we retain the usual mode of attaching the upper edge of 40 the windshield, such attachment being at the back of the hammock or at a point over the rear edge of the seat. The lower edge, however, we attach differently by providing therefor a rail similar to the rail at its upper 45 edge, and at each end of the added rail we provide a detachable connection to some point midway of the seat width.

Referring to the drawings, A is the end bar of the seat-frame, B is the wire fabric, 50 C is the mattress and D is one of the end sheets by which the seat is suspended. The windshield E is provided along its top edge with the usual rail F and along its bottom edge with a similar rail G. At each end of

the top rail is riveted a U-shaped metal plate 55 H with a keyhole slot in the bend and a space under the bend for receiving the head of a pin P on the end sheet D; the pin head enters the circular part of the slot and the neck of the pin enters the contracted part of 60 the slot so as to be retained by the plate H. Thus the two ends of the rail F are secured to the respective end sheets at a point over 65 the rear of the seat. The bottom edge of the windshield, provided with a similar rail G and a similar plate K, is secured to the end bar A of the seat-frame by means of a link R pivoted at S to the end-bar and having at its upper end a pin T which engages 70 the keyhole slot in plate K as pin P engages the slot in plate H. There is, however, this difference: the slot is reversed in plate K so that it is necessary to draw the windshield down taut to allow pin T to enter the circular part of the slot. This provides a take-up feature which keeps the pin T locked 75 in the slot and maintains an adequate tension on the windshield.

The link R thus forms a hook connection 80 between the windshield and the hammock seat. When the links R are not in use they may be turned down, as shown in dotted lines between the end of the mattress and the end sheet to be out of the way and out of sight.

By this device the windshield may be 85 easily converted into a comfortable back for using the hammock as a seat and as readily changed back into a mere windshield when the hammock is to be used as a couch.

What we claim as new and desire to secure by Letters Patent is:

1. A hammock comprising a seat frame, end sheets having their lower portions connected with the seat frame, a back windshield having top and bottom rails, lugs 95 on the upper portions of the end sheets detachably engaging the contiguous ends of the top rail of the windshield, and L-shaped links having their offset ends pivoted to the seat frame and their free ends provided with lugs positioned to engage the contiguous ends of the bottom rail of the windshield, the complementary engaging portions of the top and bottom rails and the respective lugs being positioned to maintain the windshield 100 in a taut condition when the parts are engaged.

2. A hammock comprising a seat frame,

end sheets having their lower portions connected with the seat frame, a back windshield having top and bottom rails, lugs on the upper portions of the end sheets detachably engaging the contiguous ends of the top rail with the windshield, and links each pivoted at one end to an end of the seat frame and having their free ends provided with lugs positioned to engage the contiguous ends of the bottom rail of the windshield, the complementary engaging portions of the top and bottom rails and the respective lugs being positioned to maintain the windshield in a taut condition when the parts are engaged.

3. A hammock comprising a seat frame, end sheets having their lower portions connected with the seat frame, a back windshield, plates connected to the several corners of the wind shield, said plates having key-hole slots therein, lugs on the upper portion of the end sheets engaging the slots of the plates on the upper corners of the wind shield, and links each pivoted at one end to an end of the seat frame and having their

free ends provided with lugs to engage the slots of the plates on their lower corners of the wind shields, the key-hole slots of the upper corner plates being disposed opposite to those of the lower corner plates. 30

4. A hammock comprising a seat frame, end sheets having their lower portions connected with said seat frame, a wind shield provided with top and bottom rails, U-shaped plates secured to said rails and passed around the ends thereof, said plates being provided with key-hole slots, the slots of the plates of the top rail being oppositely disposed to those of the plates of the bottom rail, lugs on the upper portions of said end sheets shaped to detachably engage the slotted U-shaped plates of the said top rail, and links pivoted to the seat frame and having lugs shaped to engage the slots of the U-shaped plates of said bottom rail whereby 40 said back sheet is kept taut. 45

Signed at Long Island City, borough of Queens, N. Y., March 20th, 1919.

GEORGE F. SISBOWER.
LOUIS E. PITTONI.
